(57) **CLAIM**

The ornamental design for a joiner part of a parasol as shown and described.

DESCRIPTION

2.1 is a front view of a joiner part of a parasol showing the new design;

2.2 is a rear view thereof;

2.3 is a left, top perspective view thereof;

2.4 is a right, top perspective view thereof;

2.5 is a top cross-sectional view of a lower portion thereof;

2.6 is a bottom view thereof;

2.7 is a top, front perspective view thereof;

2.8 is a top, rear perspective view thereof;

2.9 is a left side view thereof;

2.10 is a right side view thereof; and

2.11 is a top view thereof.

Diagonal shading in reproductions 2.3, 2.4, 2.7, 2.8, 2.9 and 2.10 indicates cross-sectional boundaries of the claimed design. Diagonal shading in reproduction 2.5 indicates a surface through which the claimed design has been cut. The broken lines in reproductions 2.3, 2.4, 2.7, 2.8, 2.9 and 2.10 show portions of the article that form no part of the claimed design.
